AERIAL TOW TARGET

Filed Dec. 31, 1947

UNITED STATES PATENT OFFICE

2,487,055

AERIAL TOW TARGET

Le Roy S. Jessen, Dayton, Ohio

Application December 31, 1947, Serial No. 794,853

4 Claims. (Cl. 273—105.3)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to aerial tow targets and particularly to a mechanism for releasing a target and replacing it with another during flight.

It is presently the practice in tow target gunnery to tow a target by means of a suitable towing plane equipped with a windlass containing the required length of cable. The target is let out on this cable and after a prearranged amount of gunnery practice has been recorded on a target it is preferably exchanged for another. Since it is impracticable to reel in the target with the windlass against the air resistance encountered, it is usual to provide mechanism at the junction between the target and the end of the cable whereby the used target is released and dropped and replaced by another, the mechanism for accomplishing this being such that the impact of the new target sent back from the tow plane will release the old target but will hold the new one for subsequent gunnery practice, each used target being in turn replaced by a new one through operation of the release mechanism.

Release mechanisms of the general character herein disclosed are presently known to the art but they are not as simple in construction nor as effective in operation as could be desired, and it is therefore an object of this invention to provide a simple, inexpensive and compact tow target exchange device which will perform this function at minimum cost and with minimum danger of failure. I attain this and other objects and meritorious features in the mechanism herein-after described, reference being had to the drawing, wherein:

Fig. 1 is an assembled side view of an embodiment of the release mechanism which is the subject of this invention.

Fig. 2 is a view similar to Fig. 1 but with a target lead line ring shown in the several positions which it takes in releasing a target after use and substituting a new one in its place.

Fig. 3 is a transverse figure taken on the line 3—3 or 3a—3a of Fig. 2, showing the cross sectional contour of the body of the device.

Like reference characters refer to like parts throughout the several views.

In the drawing, a towing cable 10 is fastened in a well known manner in a hollow conical guide 12, this method of fixing the cable being shown in Fig. 3 of my Patent No. 2,390,538 issued December 11, 1945. The cone 12 is threaded as-

2

sembled with the body 14 of the device, the two parts being joined together at 16.

The body portion 14 is slotted as at 18, Fig. 3, from the right-hand end of the body to the line 20, the slot 18 being wide enough to freely admit the triple hook 22 which is freely rotatable on the shaft 24 and is temporarily held in the position shown by a small split cotter pin 25. A plurality of rings 26 are provided, each having an ear 28 to which the target attaching line 30 of the target (not shown) is secured. The body 14 is substantially of uniform diameter throughout its length although offset as at 29, this offset being an important feature of the invention. The openings in the rings 26 are large enough to pass over any portion of the body 14 loosely as shown. The operation of the improved target exchanger is substantially as follows:

A number of rings 26, each with an attaching line 30 are assembled on the guide tube (not shown) through which the cable passes as it comes from the windlass. After the towing plane is aloft, a target may be attached to a ring 26 by the attaching line 30, and the ring placed in position A on the body 14. At this time the position of the triple hook 22 is such that the end 36 of one of the hooks keeps the ring from passing on over the body, the cotter pin 25 temporarily holding the triple hook in that position. The target is then launched through an opening in the underside of the airplane. The target then, due to air resistance, pulls the cable from the windlass in the airplane. When sufficient cable is pulled out, the operator sets a brake and the target is ready for gunnery practice. When it is desired to replace the target being towed with a new target, the new target is attached to the outer lead line whose ring is still threaded on the guide tube. The new target is then launched through the launching opening and the towing airplane flies on, pulling the cable through the ring of the lead line of the new target.

When the replacement target with its ring 26a and the exchange device meet, and the ring 26a passes over the cone 12 and onto the body 14, the ring 26a, when it reaches the position C, strikes the downwardly extending portion of the triple hook 22 at 32, and, by further rearward movement to the position B, rotates the triple hook 22 in the direction of the arrow 34 and thereby shears the cotter pin 25 and moves the hook end 36 upwardly into the slot 18, allowing the first ring 26 to pass off the rear end of the body 14, whereby the original target is dropped, and allowing the second ring 26a to take the position A whereby

its target may be towed for further gunnery practice.

There is now no further need for a cotter pin 25 to hold the triple hook nonrotative, since, due to the offset 29 of the body 14, the center 38 of the cross section of the ring 26 and the center of the shaft 24 are both in a plane parallel with the axis of the body 14. Rearward pull on the ring 26 will therefore have no tendency to rotate the triple hook and thereby drop the target. Rotation of the triple hook and dropping of the used target may be effected only by release of a new target.

The last target to be flown is released by the use of a very small release sleeve in the shape of the target itself. This sleeve travels out over the cable on the same lead line and ring assembly as the targets, releases the last target and retains itself on the exchange assembly. Its purpose from this time on is to act as a stabilizer to keep the cable from whipping while the cable is being reeled back on the windlass of the airplane.

Having described an embodiment of my invention, I claim:

1. For use in connection with a towing plane having a windlass with a cable windable thereon and a series of targets each having a lead line and a target ring at the free end of the lead line, the invention which comprises an improved target exchanger of the class which discharges a used target by the impact of a fresh target, said exchanger comprising a cylindrical body, a conical portion at the forward end of said cylindrical body adapted to receive and hold the end of a cable, said cylindrical body being of a diameter which will pass freely through a target ring and being medially slotted from the rearward end forwardly to a point near the beginning of the conical portion and being offset midway of the slotted portion in the plane of the slot, a transverse shaft near one side of the cylindrical body adjacent the offset, having its axis normal to the plane of said slot, a triple hook in the form of a wheel having three radial spokes each terminating in a circumferentially extending hook at the outer end, said wheel being rotatable on said shaft within said slot and positioned so that when one spoke and its hook is in a first position wholly within said slot, a second spoke and its hook is in a second position wholly outside said slot with its hook extending forwardly of the body, and the third spoke is in a third position within said slot with its hook protruding radially from said slot at the side of said offset portion.

2. An improved target exchanger of the class which discharges a used target by the impact of a fresh target, said exchanger comprising a cylindrical body, a forwardly tapering portion at the forward end of said cylindrical body adapted to receive and hold the end of a cable, said cylindrical body being slotted from the rearward end forwardly to a point near the beginning of the tapering portion. the rearward half of the slotted portion being offset in the plane of the slot, a shaft near one side of the cylindrical body adjacent the offset, having its axis normal to the plane of said slot, a triple hook in the form of a wheel having three radial spokes each terminating in a circumferentially extending hook at the outer end, said wheel being rotatable on said shaft within said slot and positioned so that when one spoke and its hook is in a first position wholly within said slot, a second spoke and its hook is in a second position wholly outside said slot with its hook extending forwardly of the body, and the third spoke is in a third position within said slot with its hook protruding radially from said slot at the side of said offset portion substantially as shown and described.

3. An improved target exchanger comprising a cylindrical body, slotted from the rearward end forwardly to a point intermediate the ends and having the rearward half of the slotted portion offset in the plane of the slot, a shaft near one side of the cylindrical body adjacent the offset, having its axis normal to the plane of said slot, a triple hook in the form of a wheel having three radial spokes each terminating in a circumferentially extending hook at the outer end, said wheel being rotatable on said shaft within said slot and positioned so that when one spoke and its hook is in a first position wholly within said slot, a second spoke and its hook is in a second position wholly outside said slot with its hook extending forwardly of the body, and the third spoke is in a third position within said slot with its hook protruding radially from said slot at the side of said offset portion.

4. The device of claim 3 with a shear pin extending through an opening which passes transversely through said body and through one spoke of said wheel.
